Primary Examiner — Richard Kearney*Assistant Examiner* — Liv C Anderson(74) *Attorney, Agent, or Firm* — Young Basile Hanlon & MacFarlane, P.C.(57) **CLAIM**

The ornamental design for a video light, as shown and described.

DESCRIPTION

FIG. 1 is front perspective view of a video light shown in an environment of use;

FIG. 2 is a perspective view of a video light shown in an alternative configuration of use;

FIG. 3 is a perspective view of a video light shown in another alternative configuration of use;

FIG. 4 is a front perspective view of a video light;

FIG. 5 is rear perspective view thereof;

FIG. 6 is a front view thereof;

FIG. 7 is a rear view thereof;

FIG. 8 is a first side view thereof;

FIG. 9 is a second, opposite side view thereof;

FIG. 10 is a top view thereof; and,

FIG. 11 is a bottom view thereof.

The broken lines illustrating the neck in FIGS. 1-3 are for environmental purposes, the remaining broken lines show portions of the article; all broken lines form no part of the claimed design.

1 Claim, 6 Drawing Sheets(56)
